(57) **CLAIM**

The ornamental design for a LUG WRENCH as shown and described.

DESCRIPTION

FIG. 1 is a perspective view of a LUG WRENCH according to the claimed design.

FIG. 2 is a front view of the LUG WRENCH.

FIG. 3 is an enlarged top view of the LUG WRENCH.

FIG. 4 is an enlarged bottom view of the LUG WRENCH.

FIG. 5 is a cross-sectional view of the LUG WRENCH taken along line 5-5 in FIG. 2.

FIG. 6 is an enlarged cross-sectional view of the LUG WRENCH taken along line 6-6 in FIG. 2.

FIG. 7 is an enlarged cross-sectional view of the LUG WRENCH taken along line 7-7 in FIG. 2.

FIG. 8 is a rear view of the LUG WRENCH.

FIG. 9 is left-side view of the LUG WRENCH.

FIG. 10 is right-side view of the LUG WRENCH.

The LUG WRENCH is shown with a symbolic break in its length in FIGS. 1-2, 5, and 8-10 of the drawings. The appearance of any portion of the LUG WRENCH between the break lines forms no part of the claimed design.

1 Claim, 8 Drawing Sheets
